UNITED STATES PATENT OFFICE.

DAVID T. ARREL, OF YOUNGSTOWN, OHIO.

CANOPY-CARRIAGE.

1,201,428.

Specification of Letters Patent. Patented Oct. 17, 1916.

Application filed March 22, 1915. Serial No. 16,186.

To all whom it may concern:

Be it known that I, DAVID T. ARREL, residing at Youngstown, in the county of Mahoning and State of Ohio, a citizen of the 5 United States, have invented or discovered certain new and useful Improvements in Canopy-Carriages, of which improvements the following is a specification.

My invention relates to improvements in 10 canopy coverings; I have developed it for the specific use of protecting race tracks from rain; and in that specific application it is illustrated in the accompanying drawings.

15 Figure 1 is a view in side elevation of the covering when furled and out of the way; Fig. 4 is a diagrammatic view in section (and on smaller scale) across the race track, showing the covering extended in service 20 position; Fig. 5 is a plan view, on still smaller scale, of the covering when in the extended position; Fig. 2 is a fragmentary view, illustrating the furling of the covering; Fig. 3 is a view in perspective illustrating a detail of the apparatus now to be 25 described.

Referring first to Fig. 4, which as has been said shows in cross section a race track with the covering of my invention spread above 30 it, it will be seen that the surface of the track is shown to be inclined at a low angle and to be guarded on its sides by the two fences K and H. Such are usual conditions of a race track, and it is to those conditions 35 that I adapt my invention.

The canopy covering is essentially a stretch of canvas or other suitable pliable material of sufficient width to extend above the track from side to side and protect the 40 track from rain and of proper length to serve alone or in a succession of sections to protect the entire track or so much of it as may need such protection. Upon the fence which extends along the higher side of the 45 track—which in case of a closed track will be the outside—I erect the supports and carriers for the covering when furled and for one margin of the covering when extended. These supports take the form of up- 50 rights with laterally extending arms A, fully shown in Fig. 1, and diagrammatically indicated in Figs. 4 and 5. These supports A may be suitably strengthened against the strains of service, as by the guy ropes indicated at S in Figs. 1 and 4. The canopy itself, shown in furled position in Fig. 1 and in spread position in Figs. 4 and 5, is

secured along one edge to the supports A, as is indicated in Fig. 1; its opposite edges are provided with anchoring ropes L, and 60 these anchor ropes will ordinarily be provided with block and tackle to permit of drawing taut the anchored canopy.

Upon the fence H which extends along the lower side of the track are conveniently 65 placed a succession of runways for the ropes L; these may conveniently take the form of the sheave C, illustrated in Fig. 3, and whose positions are indicated by the same reference letter C in Fig. 5. Proper anchorage for 70 the ropes L is provided beyond the fence H, such anchorage being indicated at E (compare, in this regard, Figs. 4 and 5). In addition to these essential parts of the canopy covering, means are provided for 75 the ready spreading and furling of the canopy. These means consist of a succession of supporting members G, which may be ropes or lengths of any suitable material, but which as shown and as preferably 80 used are comparatively narrow strips of canvas. These are arranged to be alternately drawn across and removed from position above the track. Adjacent the line of fence K, and preferably within it—though 85 the fence K itself might serve as the support—are set a succession of supports B (compare Figs. 1, 4, and 5). These are preferably posts, suitably guyed, as indicated at V—V in Fig. 1. Upon supports B are 90 mounted rollers, on each of which a strip G may be wound and unwound. When unwound, the free ends of the strips G are carried across the track, over fence H, and are secured to proper anchorage, indicated 95 at F (compare Figs. 4 and 5).

Fig. 4 shows that the strips G are arranged to extend beneath and support from beneath the main canopy. Ordinarily, as indicated in Fig. 5, a number of the strips 100 G will at their otherwise free ends be secured to a common rigid rod, conveniently a length of light pipe, indicated at D—D, and each length of pipe will be suitably anchored, at two or more points, as F—F. 105 When not in service the strips G will be wound up, in the position indicated in Fig. 1.

Let it be supposed that the apparatus in the furled position indicated in Fig. 1 is 100 to be applied to service and spread. First, the lengths of pipe D—D are taken and carried across the track, the strips G unwinding, and over fence H and this part

of the structure is suitably anchored at F, F, the strips G being drawn taut, with block and tackle if need be. Next, the ropes L are carried across the track, the cover as 5 it is thus gradually unfurled resting upon strips G. The ropes L are carried over their runways C, the anchorage E is made secure, and if block and tackle are used (as will ordinarily be the case) the ropes 10 L are thus drawn until the whole canopy extends taut, or substantially so, from one edge which is secured to the supports A on fence K to the other edge which, passing over fence H is anchored at E. When the 15 extended canopy is to be furled, the ropes L are first slackened and released from their anchorage E. An attendant then stands at each of the supports A, and, reaching forward above the canopy, by means of a 20 hooked instrument M (Fig. 2) picks up one after another a line of rings P with which the upper surface of the canopy is provided and slips them over the end of the laterally extending arms with which the 25 support A is provided. And it will be observed that the extremity of the arm is slightly up-turned, to facilitate this furling operation and retain the rings P as they are slipped on, one after another. As 30 these rings are slipped on the arms of supports A, the canopy will come to furled position, hanging in folds, as is indicated in Fig. 1. It will be understood that the apparatus does not require the attendance of 35 a number of men corresponding precisely to the number of supports A. I am here describing the operation as most readily performed. As a matter of fact one man can do it all,—though slowly, of necessity. 40 There will be as many lines of rings P as there are arms A and they will be spaced accordingly. When the canopy itself has thus been furled, it remains to release the strips G from their anchorage, and by the 45 turning of their supporting sheaves to wind them up, out of the way.

It will be understood that this canopy is intended primarily for the protection of the surface from rain and not for inclosing a 50 space within which men and horses may move about; but, manifestly, it is a matter of proportion, whether the canopy be such as to permit such more extended service. Ordinarily speaking, a track slopes suffi- 55 ciently from side to side to throw the surface water, but ordinarily the slope will not be sufficient to allow the canopy to rest directly on the two fences and so supported to serve its purpose adequately. Accord- 60 ingly, the support A will ordinarily be a foot and a half high, or thereabout. It should not be so high as to cause any undue difficulty in operation.

Copies of this patent may be obtained for five cents each, by addressing the "Commissioner of Patents, Washington, D. C."

The distance from fence to fence in a race track of ordinary size may be, in places 65 ninety feet. Assuming the section of canopy of Fig. 5 to be about 100 feet wide, it is about three hundred and fifty feet long; there are twelve supporting strips G, each ten feet wide, some twenty feet apart from 70 center to center, while at the ends the canopy is unsupported for fifty feet or more. A race track is ordinarily a closed track of approximately elliptical plan, and it will be understood that a succession of such canopy 75 sections as that shown in Fig. 5, with overlapping ends may cover the whole or any portion of such a track. On the curves, of course, the canopy sections may, if desired be tapered—shorter along one edge than 80 along the other. The particular dimensions suggested are merely in the way of exemplification, and are not intended to limit in any degree the invention.

While the strips G will undoubtedly 85 serve in some degree, and may be made to serve in a very appreciable degree, to reinforce the canopy and strengthen it from sagging and bellying under the weight of rain upon it, their primary use lies in facilitating the spreading and furling of the canopy, in the manner already explained. The anchorage of course may be such that tension may be increased as the canopy and the strips G stretch when wet and weighted 95 with water.

I claim as my invention:

1. In a canopy structure the combination of two parallel canopy supports a series of rollers mounted adjacent to one of said supports, a series of strips of flexible material secured one to each of said rollers and capable of being wound thereon and unwound therefrom, anchorage for said strips adjacent the opposite one of the said parallel supports, and a canopy covering supported along one edge by the support to which the said rollers stand adjacent. 100

2. In a canopy structure the combination of parallel supports, a canopy secured along 110 one edge to one of said supports, anchor ropes secured at intervals along the opposite free edge of said canopy, a succession of guide sheaves secured upon the second of said parallel supports and at intervals 115 corresponding to the spacing of the ropes along the free edge of said canopy, and anchorage adjacent said second named support.

In testimony whereof I have hereunto set 120 my hand.

DAVID T. ARREL.
